United States Patent Office

Des. 199,705
Patented Dec. 1, 1964

199,705

TYPEWRITER

Chester J. Abend, Camillus, and Thomas E. Hanson,
Syracuse, N.Y., assignors to SCM Corporation, New
York, N.Y., a corporation of New York

Filed June 4, 1963, Ser. No. 75,207

Term of patent 14 years

(Cl. D64—11)

FIGURE 1 is a front perspective view of a typewriter showing our new design;

FIGURE 2 is a top plan view thereof;

FIGURE 3 is a front elevational view thereof;

FIGURE 4 is a rear elevational view thereof;

FIGURE 5 is a right side elevational view thereof; and FIGURE 6 is a left side elevational view thereof.

The characteristic feature of our design shown herein in solid lines resides in the particular front panel disclosed having a contrasting block-like pattern extending over the major portion of its surface as shown.

We claim:

The ornamental design for a typewriter, substantially as shown and described.
